2 Claims.

(Cl. 86—23)

Patent No. 1,769,861 relates to a fuse setting machine of the type comprising two relatively rotatable setting members in which the lower setting member serving for rotating the timing ring of the fuse is temporarily connected with mechanism in motion by a coupling controlled by the insertion of a projectile and by the process of setting.

Means were also provided which adapted the setting machine to receive at the same time several projectiles and to allow the fuses of these projectiles to be set independently of one another.

The coupling of the lower setting member in each setting socket with the rotating driving device is effected by a coupling disc which is mounted rotatably and on its rotation is axially displaceable on the hub of the lower setting member, the hub being provided with a screw thread of quick pitch.

Between the lower setting member and the coupling disc there is provided a coupling spring which has one end on the setting member and the other on the coupling disc, and by its tension tends constantly to produce coupling, that is to say to turn the coupling disc. In the uncoupled position the setting member and also the coupling disc are secured by projections which respectively engage in notches in the setting member and the coupling disc, said projections being located on sleeves, one of the sleeves being axially displaceable but not rotatable on a fixed part of the housing while the other sleeve is mounted on the first sleeve so as to be axially displaceable but not rotatable thereon. In dependence on the insertion of the projectile in the setting socket, the sleeves carrying the projections are disengaged from their locked positions, so that under the action of the released coupling spring the coupling disc is coupled with the constantly rotating driving device.

With this arrangement, the setting member and the coupling disc are locked in their uncoupled position by locking members, the one being secured against rotation directly and the other by means of the first, in relation to the fixed part of the housing. Hence, when there is play between the fixed part of the housing and the inner sleeve placed directly thereon in order to secure the position of rest of the lower setting member, the setting member carrying the lower fuse setting projection when in the coupled position, can deviate to the extent of the magnitude of this clearance from the desired neutral position. With the small diameter of the housing

guide member employed for guiding the sleeve, there may be only slight play at this part, but at the setting projection there will be very considerable deviations from the zero or neutral position and, therefore, serious mistakes in the setting of the fuse. Owing to the unavoidable wear which occurs between the guiding and the guided parts, a source of error which constantly increases in the course of time is to be expected, so that even when a very fine fit is effected, no perfect remedy which remains effective for a considerable time can be obtained.

According to the invention, in order to avoid the disadvantageous effect of the play between the locking device and its guide member on the housing in the neutral or uncoupled position of the lower setting member, the locking device is subjected to the action of a member, for example a spring, which in the uncoupled position turns it constantly in the same direction until it comes to rest on the fixed housing guide. For this purpose it is particularly advantageous to make use of the coupling spring which is already available. In further development of the general idea of the invention the safety device for the coupling disc uncoupled from the drive, and the locking device for the lower setting member in the uncoupled position, are both being arranged directly on a fixed part of the housing of the fuse setting machine so as to be axially displaceable but non-rotatable thereon. Thus the coupling spring is placed between the coupling disc for the drive and the lower setting member and presses the two locking members into final positions on their fixed guide by thrusts which are constantly similarly and oppositely directed, so that faulty neutral positions due to the aforesaid play cannot occur.

A typical embodiment of the invention is shown in the drawing wherein Figs. 1 to 3 represent one longitudinal section and two cross-sections respectively through the setting sockets.

In the drawing B represents the lower setting member which carries the setting nose b and which is rotatably mounted in the housing c of the fuse setting machine. k represents the coupling disc which is mounted so as to be rotatable and axially displaceable on the hub b₅ of the lower setting member, the hub being provided with a screw thread (b₁₂) of quick pitch. g represents the driving device which is constantly in rotation. Between the setting member B and the coupling disc k there is mounted the coupling spring f₃, which rests at one end on the lower setting member B and on the other side on a

lug k_1 of the coupling disc which passes through a slot in the base of the setting member. In the neutral or uncoupled position the setting member B is secured against turning by the stop d_2 which springs into a notch b_{14} in its hub b_8 under the action of the spring f_4 , said stop being provided on the collar d_1 of the sleeve d which is mounted so as to be axially displaceable and non-rotatable on the fixed part c of the housing. Likewise the coupling disc k is secured in the neutral position against turning by a stop i_2 which moves into the notch k_2 of its hub under the influence of the spring f_5 , said projection being provided on the collar i_1 of the sleeve i which engages over the sleeve d and which is mounted so as to be axially displaceable and non-rotatable on the fixed part c of the housing. The projection i_2 engages through a slot in the collar d_1 of the sleeve d . The fixed part c of the housing is a shaft having a key c_2 on which the sleeves d and i are located by suitable keyways.

In the neutral position shown in the drawing the setting member B and the coupling disc k are each coupled directly to the fixed part c of the housing by means of the sleeves d and i carrying the projections d_2 and i_2 . The result of this is that the sleeves d and i , by means of the coupling spring f_3 placed between the coupling disc k and the setting member B , are pressed positively in opposite directions and each of the sleeves d , i is always thrust in the same direction and held in the same terminal position on the key shaft c_2 . Thus a play ϕ between the sleeve

d and the key shaft c_2 in the direction of the angle of rotation (Fig. 3) is rendered inactive as an influencing factor to obtain a faultless neutral position of the lower setting member B .

I claim:

1. A fuse setting machine comprising a housing; a guide stem fixed against rotation in the housing; a fuse setting member rotatable about the stem; a rotary drive member; a coupling device movable to couple and uncouple the said members; a pair of locking means each slidable on said stem and one for locking the fuse setting member and the other the coupling device against rotation when the drive member is uncoupled, each of said locking means being fixedly held directly on the stem against rotation; and a resilient connection between said locking means for neutralizing play between them and the stem.

2. A fuse setting machine comprising a housing; a guide stem fixed against rotation in the housing; a fuse setting member rotatable about the stem; a rotary drive member; a coupling device movable to couple and uncouple the said members; a pair of separate devices each slidable on said stem and one for locking the fuse setting member and the other for locking the coupling device against rotation when the drive member is uncoupled, each of said separate devices being fixedly held directly on the stem against rotation; and a spring between the fuse setting member and the coupling device for neutralizing play between the said devices and the stem.

ANTON GIETMANN.
